ARTIFICIAL BAIT

Philip W. Gurka, Upper Montclair, Essex
County, N.J. 07043

Filed July 29, 1968, Ser. No. 12,947

Term of patent 14 years

Int. Cl. D22—07

U.S. Cl. D22—27

3—> FIG. 1

3—> FIG. 2

FIG. 3

FIG. 1 is a perspective view of an artificial bait;

FIG. 2 is a top view; and

FIG. 3 is an enlarged sectional view taken on the line
3—3 of FIG. 1.

The broken lines are for illustrative purposes only.

I claim:

The ornamental design for an artificial bait, substantially as shown and described.
